BENCH

James E. Miller, Birmingham, Mich., assignor to Form, Incorporated, South Lyon, Mich.

Filed Apr. 25, 1972, Ser. No. 247,507

Term of patent 14 years

Int. Cl. D6—01

U.S. Cl. D6—59

FIG. 1

FIG. 2

FIG. 4

FIG. 3

FIG. 5

FIG. 7

FIG. 1 is a front perspective view of a bench showing my design.

FIG. 2 is a left side elevational view, in perspective, of such new design, the right side being a mirror image thereof.

FIG. 3 is a right, rear perspective view of the design, the left rear view being a mirror image thereof.

FIG. 4 is a plan view thereof.

FIG. 5 is a front view thereof.

FIG. 6 is a left side elevational view thereof, the right side elevational view being a mirror image thereof.

FIG. 7 is a rear elevational view thereof.

I claim:

The ornamental design for a bench, as shown and described.
